UNITED STATES PATENT OFFICE.

THOMAS C. SAWYIER, OF INDIANAPOLIS, INDIANA.

DESIGN FOR A PENHOLDER.

56,680.

Specification for Design.

Patented Nov. 23, 1920.

Application filed May 7, 1920. Serial No. 379,683. Term of patent 14 years.

To all whom it may concern:

Be it known that I, THOMAS C. SAWYIER, a citizen of the United States of America, residing in the city Indianapolis, county of Marion, and State of Indiana, have invented a new, original, and ornamental Design for a Penholder, of which the following is a specification, reference being had to the accompanying drawings, forming a part thereof.

The figure is a plan view of a pen holder, showing my new design.

I claim:

The ornamental design for a penholder, as shown.

THOMAS C. SAWYIER.
